UNITED STATES PATENT OFFICE.

MATTHEW CHARLES BELIKAN, OF CHICAGO, ILLINOIS.

SAFETY HAMMER.

Application filed September 21, 1927. Serial No. 220,948.

This invention relates to improvements in carpenters' hammers, and the object is to provide a combination of hammer head and handle so formed and assembled as to guard against the accidental flying off of the head, and by virtue of the same formation to facilitate the drawing of nails.

In the drawing

Figure 1 is a side elevation of the improved tool;

Figure 2 is an end elevation;

Figure 3 is a top edge view;

Figure 4 is a bottom edge view.

The invention comprises a hammer head having a peen portion 1, a claw portion 2 and a connecting eye portion 3. A side elevation of the eye portion 3 is rhomboidal in character as clearly shown in Figure 1, with the result that the said peen and claw portions are obliquely or angularly connected by the said eye portion, the claw portion being disposed rearwardly of the peen portion. The eye portion 3 is formed with the tapered eye 4, the same tapering and narrowing from the outer sloping face 5 to the inner sloping face 6 of the said rhomboidal eye portion. A screw hole 7 is formed through the rearwardly extended upper wall 8 of the said eye portion 3. A handle 9 is provided, the same having an expanded and sloped outer end 10 adapted to conform to the eye 4.

In inserting the handle into the head, the rear end 11 of the handle is passed through the eye 4 from the side 5 of the eye portion, so that the expanded end 10 seats within the tapered eye 4 in such manner that the ham-

mer head cannot fly off of the handle in the process of ordinary use, being restrained by the said expanded end 10. At the same time the sloping face of the said expanded end 10 prevents the peen portion 1 from forcing outwardly and out of its normal position perpendicular to the extended axis of the handle.

The result of this structure is that the handle need not be wedged tightly into the eye, but may rest therein rather loosely so as to facilitate removal of the handle when desired. A screw 12 is passed through the screw hole 7 into the handle, as means for preventing the hammer head from sliding back upon the handle. In addition to the safety features of the structure shown, the form of hammer here provided facilitates the pulling of long nails, as the tool first has a fulcrum upon the outwardly curved face 5 of the claw portion 2 and finally upon the sloping faces 5 and 10 of the eye portion and handle end.

The use and operation of the tool are described in the foregoing specification.

Any minor changes may be made in the structure within the scope of the appended claim.

I claim:

A hammer head having peen and claw portions obliquely connected by a rhomboidal eye portion bringing the claw portion back from the front of the eye portion so that the latter may fulcrum on the end of a handle received in the eye portion.

In testimony whereof I affix my signature.

MATTHEW CHARLES BELIKAN.
